SOFA BACK CONSTRUCTION

William F. Richardson, Carthage, Mo., assignor to Flex-O-Lators, Inc., Carthage, Mo., a corporation of Missouri

Application July 29, 1953, Serial No. 370,919

2 Claims. (Cl. 155—179)

This invention relates to new and useful improvements in sofa construction, and relates particularly to the frame and spring portions of sofa backs.

The principal object of the present invention is the provision of a sofa back construction which provides a "soft" or resiliently yieldable edge at the upper edge of the back, in a construction utilizing sinuous or "zig-zag" springs. This type of spring comprises a plurality of wires each bent into sinuous form in a plane, being attached at its opposite ends respectively to more or less rigid support members at the upper and lower edges of the sofa back, and arched forwardly between its ends. If the upper edge of the sofa back is to be of the "soft" type, it is evident that the upper support of the sinuous wires must be yieldably supported for considerable movement. Heretofore this lack of a rigid support member at the top has virtually eliminated the use of sinuous springs in "soft-edge" sofa backs, since the downward drag of the backs of persons using the sofa tended to pull the upholstery and springs of the back downwardly. The upper ends of the sinuous springs did not have sufficient vertical support, and furthermore sinuous springs do not lend themselves efficiently to support at intermediate points. The present invention contemplates the provision of means, in a sofa back of the class described, whereby the upper ends of the sinuous springs are provided with virtually rigid vertical support, but whereby said upper spring ends are left free to move resiliently in a direction at right angles to the plane of the back, thereby imparting the desirable "soft edge" characteristic to the sofa back.

Other objects are simplicity and economy of construction, and efficiency and dependability of operation.

With these objects in view, as well as other objects which will appear in the course of the specification, reference will be had to the drawing, wherein:

Fig. 1 is a front elevation view of a sofa embodying the present invention, with the entire seat portion and all of the upholstery omitted.

Fig. 2 is a sectional view taken on line II—II of Fig. 1, with the upholstery layers shown attached to the back.

Fig. 3 is an enlarged fragmentary sectional view taken on line III—III of Fig. 1.

Fig. 4 is an enlarged fragmentary sectional view taken on line IV—IV of Fig. 1.

Fig. 5 is an enlarged fragmentary sectional view taken on line V—V of Fig. 1.

Fig. 6 is a fragmentary sectional view taken on line VI—VI of Fig. 5.

Fig. 7 is an enlarged fragmentary sectional view taken on line VII—VII of Fig. 1.

Fig. 8 is an enlarged fragmentary sectional view taken on line VIII—VIII of Fig. 1.

Fig. 9 is a fragmentary sectional view taken on line IX—IX of Fig. 8.

Like reference numerals apply to similar parts throughout the several views, and the numeral 2 refers to a sofa frame constructed of wood or other suitable material and including a pair of end frames 4. Each of said end

frames comprises a front upright 6, a rear upright 8, a base member 10 connecting the lower ends of said uprights, a horizontal arm member 12 connecting the upper end of upright 6 with an intermediate point of upright 8, and a cross bar 14 extending between said uprights intermediate base member 10 and arm 12. Said end frames are connected by front and rear base members 16 and 18. Rear uprights 8 extend above arms 12 to form a portion of the frame for the sofa back, said back frame being completed by a horizontal top rail 20 extending between and fixed to the upper ends of uprights 8, and a horizontal bottom rail 22 extending between and fixed to cross bars 14, rail 22 being parallel to and spaced forwardly from rail 20. Rail 20 is supported at intermediate points by a pair of support posts 24 affixed at their upper ends to said rail and at their lower ends to rear base member 18. A wing 26 is formed in connection with each end frame 4 by a board inserted and affixed to the angle between the upper surface of arm 12 and rear upright 8.

A plurality of sinuous wire spring elements 28 are disposed substantially vertically in horizontally spaced apart relation along the back frame. Each of said wires is bent sinuously to form a series of parallel reaches connected by arcuate bends, as clearly shown in Fig. 1. The lowermost reach of each spring is mounted pivotally in a sheet-metal clip 30 affixed to the forward face of bottom rail 22 (see Fig. 4). The uppermost reach of each spring is pivotally attached by a sheet metal clip 32 to a relatively heavy steel anchor rod 34 spaced forwardly from and parallel to top rail 20 (see Fig. 3). Said anchor rod is held resiliently in spaced relation from said top rail by a plurality of substantially V-shaped springs 36 also formed of sinuously bent wire, one end of each of said springs being attached to rod 34 by its inclusion in one of the clips 32 attaching springs 28 to said rod, and the other end of said spring being pivotally attached to the forward face of the top rail by means of a clip 38. The number of springs 36 used may of course be varied as desired. It is apparent also that various other types of compression springs could be used in place of springs 36.

Rod 34 is supported vertically at spaced apart points along its length by a series of support rods 40 disposed just behind and approximately parallel to the spring plane 45 determined by springs 28. The upper end portion of each rod 40 is carried slidably in the leg portion of a T-shaped tubular member 42, and the cross-arm portion of said T-member is fitted slidably on rod 34 for pivotal movement thereon (see Figs. 5 and 6). The lower end portion of each rod 40 is bent at right angles and secured pivotally in a sheet metal clip 44 secured to bottom rail 22 in rearwardly spaced relation from springs 28.

Rod 34 is secured against movement in a direction parallel to its axis by a pair of cranks 46 normally substantially parallel to rods 40, and associated respectively with the frame wings 26 at each end of the frame. One end of each crank is bent at right angles to the body of the crank, and is disposed pivotally in a flanged tubular bearing 48 which is countersunk and fixed in frame wing 60 26 (see Figs. 8 and 9). The free end portion of the crank is also bent at right angles to the body of the crank, and is disposed coaxially with the adjacent end portion of rod 34. A tubular member 50 is welded or otherwise fixed to the free end of crank 46, and the associated end of rod 65 34 is fitted pivotally therein. Sinuous springs 28 are braced against lateral movement at intermediate points in their lengths by a series of wire links 52 extending between and looped about convolutions of each successive pair of springs.

Fig. 2 shows a representative, though in no way restrictive, mode of attaching upholstery to the previously described frame and spring construction. The padding

layer 54, which may be felt, fiber, or other suitable material, is laid over the forward face of springs 28, being included between a decorative outer cover fabric 56 and an inner protective fabric 58 which may be of textile, wire, cords, or other material and which is disposed between the padding and the springs to prevent the padding from working into the spaces between the springs. At their lower edges, the cover and protective fabrics are secured to the lower side of bottom rail 22 as by tacks 60. At their upper edges said fabrics are led over rod 34 and thence over the top of top rail 20, and tacked to the rearward surface of said top rail as at 62. The seat portion of the sofa, and the padding and upholstery for the arms and other portions form no part of the present invention, and are not shown.

In operation, it is apparent that the downward drag of the backs of persons using the sofa can not pull the springs and upholstery forming the back downwardly out of shape, said springs and upholstery being supported firmly against downward movement by rods 40. At the same time, due to the fact that rods 40 are pivoted so that the upper ends thereof can move freely toward top rail 20, being restrained only by compression springs 36, the "soft edge" characteristic is retained along the upper edge of the back. It is apparent that since rods 40 and cranks 46 are of different lengths, the upper ends thereof will describe different arcs as rod 34 is forced rearwardly toward top rail 20, thus causing a slight flexing of rod 34. However, the pivotal movement of rod 40 and cranks 46 is sufficiently short and the yieldability of rod 34 is sufficiently great to compensate easily for this movement. The rotatability of the end portions of rod 34 in the tubular socket 50 of cranks 46 prevents any possibility that the cranks could impart any torsional strain to said rod, which might otherwise tend to deform springs 28 and 36.

Although I have shown and described a specific embodiment of my invention, it is readily apparent that many minor changes of structure and operation could be made without departing from the spirit of the invention as defined by the scope of the appended claims.

What I claim as new and desire to protect by Letters Patent is:

1. A sofa back construction comprising a frame including substantially parallel top and bottom rails disposed rigidly in spaced apart relation and extending from side to side of the sofa, an anchor rod substantially parallel to and spaced forwardly from said top rail, a plurality of vertically extending spring elements disposed in spaced relation along said rails each of said spring elements being secured at its lower end to said bottom rail and at its upper end to said anchor rod, compression springs extending between and attached at their opposite ends respectively to said anchor rod and said top rail, a plurality of substantially vertical support rods each connected at its lower end to said bottom rail for pivotal movement about an axis parallel to said anchor rod, means connecting the upper end of each of said support rods to said anchor rod, a pair of cranks mounted pivotally in said frame respectively at the opposite ends of said anchor rod, the axis of said cranks being parallel to but offset below said anchor rod, and means connecting the free ends of said crank respectively to the opposite ends of said anchor rod, whereby longitudinal movement of said anchor rod is prevented.

2. The structure as recited in claim 1 wherein said means connecting each of said cranks to the anchor rod comprises a socket affixed to the free end of said crank, whereby the corresponding end of said anchor rod is fully seated and axially oscillatable.
